UNITED STATES PATENT OFFICE.

WILLIAM H. BRYANT, OF NORTH AMHERST, OHIO.

STONE-CHANNELING MACHINE.

SPECIFICATION forming part of Letters Patent No. 471,265, dated March 22, 1892.

Application filed July 13, 1891. Serial No. 399,272. (No model.)

To all whom it may concern:

Be it known that I, WILLIAM H. BRYANT, a citizen of the United States, residing at North Amherst, in the county of Lorain and State 5 of Ohio, have invented certain new and useful Improvements in Stone-Channeling Machines; and I do hereby declare that the following is a full, clear, and exact description of the invention, which will enable others skilled 10 in the art to which it appertains to make and use the same.

My invention relates to stone-channeling machines; and the invention consists in a sectional lever having a central pivot-point 15 or fulcrum and a compressible buffer of suitable material on either side of the fulcrum and between the lever-sections, all as herein-after fully described, and particularly pointed out in the claims.

20 Figure 1 is a side elevation of a portion of the frame-work of the machine and the lever and the mechanism immediately connected therewith. Fig. 2 is a view corresponding to Fig. 1 in all particulars, except that in this 25 view there is a modification in the construction of the lever, in which the fulcrum portion of each lever-section is a separate casting, and the lever consists of the bars proper extending through these castings and fastened therein. Figs. 3, 4, and 5 are details of the upper and lower fulcrum castings shown in Fig. 2, and serving to illustrate more clearly the method of connecting the parts, as hereinafter more fully described. Fig. 6 is a 30 transverse section on line $\alpha\alpha$, Fig. 2, illustrating the fulcrum and adjusting mechanism of the lever. Fig. 7 is an enlarged view of the upper portion of Fig. 6, as shown in said figure. Fig. 8 shows a detail of the 35 clamp for the hand-wheel to keep it from rising when turned. Fig. 9 is a detail of the fulcrum-pin, and Fig. 10 a detail of the locking-plate therefor. Fig. 11 is a modification of the lever-supporting mechanism, showing 40 two pivots.

45 A represents the main frame, and B the supporting-wheels.

C is the usual operating-disk, and c the crank-pin, through which power is applied to 50 the lever. The lever consists of two parts D and E, one overlapping the other about half the length of each and having a central ful-

crum or pin d, on which they are pivotally supported. At either side of this pivot or fulcrum and between the two sections of the 55 lever are compressible buffers F, preferably of rubber; but other suitable material or form of spring may be employed, and the said buffers are held in position by plates f, fixed to the respective levers. These buffers or springs 60 are designed to give the necessary elasticity to the lever.

In Fig. 1 the lever-sections are shown as made in a single piece, including the fulcrum or central portion, and to give them the 65 requisite strength it is necessary to produce them by drop-forging instead of casting; but, owing to their peculiar construction at the pivot-point, I have found that drop-forging is tedious and expensive, and hence prefer the 70 method of making and the construction shown in Fig. 2. In this construction I employ separate cast-steel or equivalent fulcrum-sections H, one of which has ears h and the other a tongue h', Fig. 6, with eyes for 75 the fulcrum-pin d. A corresponding construction occurs in Fig. 1, so far as the method of connecting the two sections is concerned. The levers D and E may then be made of 80 wrought iron and projected through the fulcrum-sections and locked therein by keys g, as shown in Figs. 3 and 4, or in any other suitable way. Now in order that the fulcrum of the lever may be adjusted or raised and lowered to meet the requirements of the work, I 85 provide a suitable supporting-frame for the lever at or about its pivot-point, consisting in this instance of two front posts I and a corresponding rear standard I', preferably made a 90 part of the supporting-frame, though this is not necessary, and the four posts are connected at the top by a plate i, which forms a bearing and support for the hand-wheel L. This wheel is threaded to engage the adjusting-rod N, and at its lower end the said rod is 95 rigidly secured to the yoke M, which reaches down over the two lever-sections on both sides thereof and has eyes for the pivot or fulcrum-bolt d. To keep the hand-wheel 100 down to working position at all times, I place a threaded clamping-ring m on the neck l thereof, which neck extends through beneath the plate D far enough to be engaged by said clamp. The clamp turns with the hand-wheel

and prevents it from getting away from working position.

The pivot or fulcrum bolt or pin d is provided with a head having an oblong tongue 5 d' , and a plate d'' , Fig. 10, attached to the yoke M , has a slot to match said tongue and engages the same to prevent the bolt from turning, and thus preventing its wearing on the yoke.

10 In Fig. 11 I show a modification of the lever connections, in which each lever-section has a separate fulcrum d on the yoke M , and the buffers F are arranged on these levers just as they are in the other forms of lever 15 shown. The invention is thus shown to be susceptible of more or less modification in and about the pivot-point of the lever, and such modification may be made without departing from the spirit of the invention.

20 Having thus described my invention, what I claim as new, and desire to secure by Letters Patent, is—

1. In a channeling-machine, a sectional cutter-lever pivoted at the center where the ends 25 of the sections overlap, and spring-buffers on opposite sides of the pivot-point between the lever-sections, substantially as described.

2. In a channeling-machine, a cutter-lever consisting of two sections overlapping each 30 other, a central pivot-support for said sec-

tions, and springs between the overlapping portions of the sections, substantially as described.

3. In a channeling-machine, a lever formed of two sections, one above the other and having spring-buffers between them, and an adjustable yoke in which the inner ends of the sections are pivoted, substantially as described. 35

4. In a channeling-machine, a lever for operating the cutters, consisting of two sections arranged one above the other with a space between, projections on said sections connected by a pivot-bolt, and buffers in the space between the sections, substantially as 40 described.

5. In a channeling-machine, the lever consisting of two fulcrum-pieces having lateral projections with eyes for the pivot-bolt bars extending through said pieces on both sides 45 of the pivot-point, and buffer-springs between the inner end of each bar and the body of the other bar, substantially as described.

Witness my hand to the foregoing specification this 8th day of July, 1891.

WILLIAM H. BRYANT.
